DESIGN FOR A BUCKLE

Herbert G. Whitehouse, Newark, N. J.

Application January 11, 1937, Serial No. 66,999

Term of patent 3½ years

To all whom it may concern:

Be it known that I, Herbert G. Whitehouse, a citizen of the United States of America, residing in Newark, county of Essex, and State of New Jersey, have invented a new, original, and ornamental Design for a Buckle, of which the following is a specification, reference being had to the accompanying drawing, forming part thereof.

Fig. 1 is a perspective view of a buckle showing my new design.

Fig. 2 is a plan view of a buckle as shown in Fig. 1.

I claim:

The ornamental design for a buckle substantially as shown.

HERBERT G. WHITEHOUSE.
